CLAIM

The ornamental design for a water closet, as shown and described.

DESCRIPTION

FIG. 1 is a top plan view of a water closet showing my design;

FIG. 2 is a bottom plan view thereof;

FIG. 3 is a front elevational view thereof;

FIG. 4 is a rear elevational view thereof;

FIG. 5 is a left side elevational view thereof, the right side being a mirror image for the left side shown, except for the omission of a flush handle; and

FIG. 6 is a perspective view thereof.
